APPARATUS SENSITIVE TO ATMOSPHERIC CONDITIONS

Albert T. Matthews, Thomaston, Ga., and Charles C. Cadden, Akron, Ohio, assignors to The B. F. Goodrich Company, New York, N. Y., a corporation of New York

Application January 6, 1936, Serial No. 57,698

3 Claims. (Cl. 297—1)

This invention relates to apparatus sensitive to atmospheric conditions and more especially to apparatus sensitive to both the temperature and humidity of the atmosphere.

In numerous industries and in buildings it has been found necessary or desirable to condition the atmosphere so as to provide suitable atmospheric conditions for handling materials and to make the atmosphere more conducive to good health.

Hygrometers of the absorption type have been generally used to determine the relative humidity of the atmosphere and similar devices have been used to control humidifying apparatus. Such devices however have been inefficient in operation due to the fact that at least they have only approximately determined the relative humidity of the air and have not been responsive to temperature change, and over the range of temperatures experienced in the hottest weather the hygroscopic material used as the sensitive element of the device has not been responsive to slight changes of humidity.

The present invention aims to provide apparatus wherein a plurality of elements, one of which is sensitive to moisture, and another of which is sensitive to temperature changes, are so combined as more effectively to indicate the atmospheric condition or to control such condition.

The principal objects of the invention are to provide efficiency, accuracy, and simplicity in apparatus.

Other objects will appear from the following description and the accompanying drawing.

Of the drawing:

Fig. 1 is a front elevation of the preferred form of apparatus showing it as used to control the humidity of the air, parts being broken away.

Fig. 2 is a vertical, sectional view taken on line 2—2 of Fig. 1.

Fig. 3 is a rear elevation of the same.

Referring to the drawing, the device in its preferred form includes a stationary frame comprising a pair of rods 10, 10' fixed in parallel spaced relation to a bracket 11 at their lower ends and a pair of spacer bars 12 and 13. A similarly disposed pair of rods 14, 14', are fixed to a cross head 15 and are slideably mounted in apertures formed in bars 12 and 13. An arm 16 is pivoted at its center on a screw 17 having threaded engagement with spacer bar 12, the arrangement being such that when the screw 17 is loosened slightly the arm 16 may be turned thereon as a pivot but when the screw is tightened the arm 16 is clamped to the bar. One end of the arm 16 is

turned outwardly and to this is fixed by a bolt 18 one end of an interrupted cylindrical ring 19 comprising a bimetallic thermo-sensitive element. The inner layer of the ring 19 is preferably formed of zinc and the outer layer of steel, the two layers being fastened together throughout their extent as by rivets and solder the arrangement being such that as the temperature increases the ring attempts to straighten and increases in radius.

An annular graduated disc 20 is fixed to the arm 16 by screws 21, 21' and spacers 22, 22'. An adjustable stop screw 23 is threaded through the cross head 15 so as to rest upon the bimetallic ring 19, and is held in adjustment by a jamb-nut 15 24. An indicating mark 25 is formed on the cross head 15 near the graduated perimeter of the disc 20. The cross head 15 will be raised by increases of temperature and lowered by decreases of temperature and the amplitude of such movements will be controlled by the relative setting of the arm 16 with the cross bar 12 inasmuch as by this setting the effective length of the bimetallic element 19 from its point of attachment at 18 to the screw 23 is adjustably determined. 25

An annular plate 26 is supported above the cross-head 15 at a fixed distance therefrom by a pair of rods 27, 27'. A stud 28 rotatably mounted through a central aperture in plate 26 is formed with a threaded portion 29 and an enlarged shoulder 30 below the plate and a squared portion 31 above the plate. An adjusting wheel 32 having a graduated depending rim 33 engages the squared portion of the stud and is held thereon by a nut 34. An index finger 35 fixed to the plate 26 extends in close relation to the graduated rim to indicate its adjustment.

An internally threaded cap 36 engages the threaded end 29 of the stud and is provided with a cross bar 37 which slideably engages the rods 27, 27'. A pair of coil springs 38, 38' of the compression type encompass the rods 27, 27' and resiliently hold the plate 26 and cross bar 37 in spaced relation. The cap 36 is formed with a depending hook 39 adapted to support the upper 45 end of a strip 40 of hygroscopic material the lower end of which is attached to a cross head 41 slideably mounted on rods 10, 10'. The strip 40 may be formed of any suitable material having the property of changing its length under the 50 influence of moisture. The preferred material is a strip of gold beaters skin which contracts when dry and expands when damp.

While the described mechanism may be used to record the combined effect of moisture and 55

temperature by connecting the cross head 41 to suitable indicating mechanism, the device may also be used to control the addition of moisture to the atmosphere for the purpose of conditioning the air. For this purpose the cross head 41 may be directly connected to the gate 42 of a valve 43 adapted to control the emission of air from a pipe 44 to the nozzle 45 of an atomizer, the water being drawn from a suitable vessel 46 by suction created by the high velocity of the air across the suction tube 47.

In the operation of the device reduction of moisture in the atmosphere causes the strip 40 to shorten and open the valve 43 until such time as the surrounding air is provided with sufficient moisture to meet the desired requirement whereupon the valve closes. Increase in temperature causes the strip 40 to be raised by an amount depending upon the position of the dial 20. The strip 40 may also lengthen under the increased temperature, such lengthening being more or less compensated for by the position of the dial 20. The movements caused by the changes in temperature and humidity are compounded to produce resulting movement of the valve. A device so constructed will provide a greater amount of moisture in the atmosphere at elevated temperatures and a lower amount at reduced temperatures than a device responsive merely to the humidity of the air and is very desirable for use in conditioning the air in textile mills and other factories where high humidity is desirable.

The temperature responsive element 19 may also be made with the layer having the higher expansibility, such as zinc, on the outside and the layer of lower expansibility, such as steel on the inside, in which case the device will provide a greater proportion of moisture at reduced temperatures and a lower proportion at elevated temperatures and the device will be useful in conditioning air in dwellings, offices, theatres, and other buildings where it may be desired to lessen the relative humidity during hot weather and increase it during cold weather to bring the indoor conditions within the range of greater comfort.

We claim:

1. Apparatus sensitive to atmospheric conditions, said apparatus comprising an element responsive to humidity changes, an element mov-

able in the vertical direction in response to temperature changes, a carrying structure interposed between said elements and resting with at least a part of its weight upon the temperature responsive element to follow the vertical movements thereof, said carrying element including adjustable means for varying the vertical position of said carrying structure with relation to said temperature-responsive element to compensate for adjustment of said temperature-responsive element, the humidity responsive element being suspended from said carrying structure and movable therewith, and a control element mounted for operation by movement of said humidity responsive element.

2. Apparatus sensitive to atmospheric conditions, said apparatus comprising an element responsive to humidity changes, a temperature responsive strip element mounted at one of its ends for flexure in increasing vertical increments away from said end under temperature changes, a carrying structure resting with at least a part of its weight upon said strip element to follow the vertical movements thereof, the humidity responsive element being supported by said carrying structure, means for adjusting the position of said carrying structure along the strip element toward and away from the mounted end of the latter to vary the degree of transmitted movement, and a control element mounted for operation by movement of the humidity responsive element.

3. Apparatus sensitive to atmospheric conditions, said apparatus comprising an element responsive to humidity changes, a temperature responsive strip element circularly disposed and mounted at one of its ends for flexure in increasing vertical increments away from said end under temperature changes, means for adjusting said element rotatively about a horizontal axis, a carrying structure resting with at least a part of its weight upon the uppermost portion of said strip element to follow the vertical movements thereof, the humidity responsive element being suspended from said carrying structure and a control element mounted for operation by movement of the humidity responsive element.

ALBERT T. MATTHEWS.
